UNITED STATES PATENT OFFICE.

EDWARD R. LINEBAUGH, OF BARBERTON, OHIO, ASSIGNOR TO THE DIAMOND MATCH COMPANY, OF CHICAGO, ILLINOIS, A CORPORATION OF ILLINOIS.

SHEET-REGISTERING DEVICE.

Application filed October 21, 1924. Serial No. 744,872.

This invention relates to sheet registering mechanisms for Gordon printing presses and the like, and particularly to the mechanism employing a unitary reversible element mountable and operable to effect the requisite registry movement of the sheet toward either the left or the right hand side of the printing press platen, as desired. A form of such mechanism is set out in Letters Patent of the United States No. 1,399,064, dated December 6, 1921, to which reference may be had.

The object of the present invention is to provide a registry device of novel construction which not only is positive and reliable in its operation, but possesses in a much higher degree than the patented device the merits of stability and durability.

To this end the invention comprises novel features of construction and combinations of parts which will be hereinafter described and claimed.

In the drawings—

Figure 1 is a plan of a platen, and adjuncts, equipped with a reversible sheet registering device embodying my present invention, said device being mounted to shift the sheet from right to left of the platen, and the gripper bar being shown in down position.

Fig. 2 is a partial plan view similar to Fig. 1, but showing the gripper bar in raised position and the registering device shifted toward the left of the platen.

Fig. 3 is another partial plan view similar to Fig. 1, but showing the sheet registering device in reversed position to shift the sheet from left to right.

Fig. 4 is a longitudinal vertical section on the line 4—4 of Fig. 2.

Fig. 5 is a similar section on the line 5—5 of Fig. 1.

Fig. 6 is a transverse vertical section on the line 6—6 of Fig. 2.

Referring to the drawings, 10 designates the platen of an ordinary Gordon press, and 11, 12 designate the end and side stops, respectively, for the sheets of paper imposed on the platen.

13 designates an oscillatory gripper bar mounted at one end of the platen, and 14 designates spaced-apart gripper fingers carried by said bar and adapted to be swung thereby at intervals upon and from the successive sheets on the platen, as usual.

Fast on the end of the platen, adjacent the gripper bar, is a bracket 15 upon which is adapted to be pivotally mounted an oscillatory lever comprising a bevel gear sector 16 and a tail portion 17. In the present instance the tail portion is slotted to receive one end of the registering arm 18, and means, such as a set-screw 19, is provided to secure the arm fixedly yet detachably to the tail portion. The lever is adapted to be detachably and pivotally mounted on the bracket 15 by means such as a screw 20 screwed into a suitably located tapped hole 21 in the bracket, the lever being positioned with its tail portion projecting toward the right or the left hand side of the platen as occasion may require.

22 designates a double acting gear rack, which is detachably secured to the gripper bar by means such as a screw 23 entered in one or the other of two suitably-disposed screw holes 24 in the bar, so that the teeth of the gear sector mesh with one side or the other of the rack teeth according to the location, right or left, of the sector 80 teeth. The rack teeth are formed on and transversely of the body of the rack and are of arcuate and angular contour in respect to the beveled teeth of the sector, as illustrated, so that the interlocking engagement 85 of the respective teeth is constant irrespective of the up or down position of the gripper bar. Hence the sector, during the forward or active movement of the gripper bar and its rack toward the platen, is positively 90 turned in a short arc about its axis 20, and then in the back stroke of said bar the sector is returned to its original position.

When the rack member and the sector are mounted in either co-operative location on the gripper bar and bracket, provision is afforded for the effective right or left hand operation of the sector during the active movement of the gripper bar, as desired. In Figs. 1 and 4 the relative position of the rack and sector lever for left hand registration is shown, and in Figs. 3 and 5 their relative position for right hand registration is illustrated.

The registering arm, when it is secured to the tail piece of the detachably mounted sector lever as above described, overhangs the platen in a path between the end stops 11, and said arm thus partakes of the oscillatory motion imparted to the sector by the 110

- vibrating gear rack. The forward end of the arm 18 is provided with a spring clip 25 which is formed and arranged to grasp and hold the end of a sheet of paper (a) inserted therebetween and supported on the platen, as usual; whereby during the movement of the arm toward the right or left hand side of the platen, as prescribed by the particular mounting of the sector lever 5 on the bracket 15, the sheet is bodily shifted in relation to the end and side stops in a manner to effect the requisite endwise and right or left hand registration of the sheet on the platen.
- 10 15 The gripper bar and bracket may be respectively provided, similarly to the previously patented construction, with additional screw holes so disposed that the sector lever and rack can be located at different 20 relative positions in respect to the platen in order to operate upon sheets of a different size or thickness, whether the device be positioned for either right hand or left hand registration.
- 25 I do not limit my invention to the details of construction herein disclosed, as the same may be modified within the spirit of the invention and the scope of the appended claims.
- 30 I claim—
1. In a printing press having a platen and sheet stops thereon and having a vibratory

gripper bar co-operating with said platen, a sheet-registering device comprising an oscillatory bevel gear member detachably supported adjacent the platen in either of two oppositely-acting positions, as desired, a sheet-registering arm detachably secured to said gear member and operable thereby, and a double acting gear rack carried by the 40 gripper bar and adapted to be located thereon in engagement with the teeth of the oscillating gear member in either acting position of the latter, the teeth of said gear rack being of arcuate and angular contour 45 in respect to the beveled teeth of the sector.

2. In a printing press having a platen and sheet stops thereon and having a vibratory 50 gripper bar co-operating with said platen, a sheet-registering device comprising an oscillatory bevel gear member mounted adjacent the platen, a sheet registering arm carried by said gear member and operable thereby, and a gear member carried by the 55 gripper bar and having teeth of such arcuate and angular contour that they are in constant mesh with the bevel teeth of said gear member during the vibration of the 60 gripper bar.

Signed at Barberton, in the county of Summit and State of Ohio this 18th day of October, A. D., 1924.

EDWARD R. LINEBAUGH.
